Primary Examiner — John R Yeh

(57) **CLAIM**

The ornamental design for a compact ironing station, as shown and described.

DESCRIPTION

FIG. 1 is a front-top perspective view of a compact ironing station showing my new design;

FIG. 2 is a front-bottom perspective view thereof;

FIG. 3 is a rear-top perspective view thereof;

FIG. 4 is a rear-bottom perspective view thereof;

FIG. 5 is a front elevational view thereof with the rear elevational view being mirrored thereto;

FIG. 6 is a left elevational view thereof;

FIG. 7 is a right elevational view thereof;

FIG. 8 is a top plan view thereof; and,

FIG. 9 is a bottom plan view thereof.

The broken lines depict portions of the compact ironing station that form no part of the claimed design.
